UNITED STATES PATENT OFFICE.

CHARLES F. GESCHICKTER, OF WASHINGTON, DISTRICT OF COLUMBIA.

DOOR AND WINDOW SCREEN HINGE.

Application filed April 3, 1924. Serial No. 704,048.

To all whom it may concern:

Be it known that I, CHARLES F. GE-
SCHICKTER, a citizen of the United States,
residing at Washington, in the District of
5 Columbia, have invented certain new and
useful Improvements in Door and Window
Screen Hinges, of which the following is a
specification.

According to the present practice in screen
10 doors, when it is desirable to take them
down for the winter season it is necessary
to remove the hinge from the main door
jamb thus leaving unsightly screw holes in
the face of the main door jamb. Another
15 practice is to remove the hinge pintle thus
leaving one of the hinge leaves on the main
door jamb which is objectionable because
said leaf projects within the door opening
as an obstruction which is likely to tear the
20 clothes of people passing through the doorway,
and also is unsightly.

The object of my invention is to provide
a hinge and its hanging plate whereby the
hinge may be bodily removed with the screen
25 door without defacing the main door jamb
or leaving any projections thereon.

A further object of my invention is to
provide a hinge for a screen door which
does not require any screws to fasten the
30 screen hinge to the door jamb; and with
these and other objects in view my invention
consists of the parts and combination of
parts as will hereinafter be more fully set
forth.

35 In the drawing:

Figure 1 is a perspective view of a portion
of a door and its jamb, my improved hinge
being shown attached thereto.

Figure 2 is an enlarged vertical sectional
40 view through the jamb showing my invention.

Figure 3 is an enlarged detail perspective
view of the upper edge of one of the hinge
leaves.

45 Figure 4 is a rear elevation of my improved
face plate and its associated parts removed.

The reference numeral 1 designates a
window or door jamb to which the screen
door, or window screen, 2 is hinged.

50 My improved hinge comprises a leaf 3
having the usual screw openings 4 and pintle
5. The other leaf member, which is design-
ated by the reference numeral 6 comprises
a flat plate without perforations, or screw
55 openings, and is secured to the leaf 3 by
means of the pintle 5.

The hinge leaf 6 is provided in one face
and at its upper edge with a recess 7, which
will be hereinafter referred to. On the back
of the leaf 6 is provided a projection 8',
60 which projection is, preferably, immediate-
ly behind the recess 7 and at the top edge
portion of the leaf 6.

The hanging plate especially designed to
be used with the special hinge just above
described is provided with screw openings
8 in its respective end portions. Intermedi-
ate the end portions 9 is a recess 10 formed
in the face of the plate with shoulders 11 at
each end of the recess. At the upper end of
the recess 10 I form an opening 12 through
the plate which is adapted to receive the
projection 8' on the leaf hinge 6 when the
leaf hinge 6 is seated in the recess 10, said
projection and recess 12 cooperating with
75 the shoulders 11 to sustain the vertical pres-
sure of the load of the door.

Immediately above the slot 12 in the face
plate there is a slot 13 constituting the slide
way and guide for the bolt 14, which bolt
80 has a stem 15 and an operating handle 16,
said operating handle projecting into a slot
17 formed through the plate in its upper end
portion. To hold the bolt on the face plate
I secure a block 18 on the rear face of the
85 plate, which block is provided with a slide-
way 19 in which the stem 15 of the bolt
slides. A spring 20 is secured to the block
18 at its lower end and projects inwardly
90 toward and bears upon the stem 15 of the
bolt whereby the bolt is held tight upon its
seat in the slot 19 against accidental dis-
placement or movement.

When the hinge leaf 6 is in its proper po-
sition in the recess 10 of the face plate, with
the projection 8 seated in the slot 12, the
hinge is locked in the recess by pushing
down the bolt 14 by its handle 16 until the
bolt is fully seated in the recess 7 of the
hinge leaf 6.

100 From the above it will be seen that all that
is necessary to hang a screen door is to have
the hinge member 3 secured to the screen
door and then place the door in position
with the hinge leaf 6 in the recess 10 of the
face plate on the door jamb, and when the
parts are in this position the screen door is
securely fastened to the door jamb by shov-
ing the bolt 14 down into the recess 7 of the
hinge leaf 6 whereby the door is securely
105 hung.

110 When it is desired, as for instance, for the

winter season, to remove the screen door all that is necessary to do is to open the screen door and push the bolt 14 upwardly and entirely out of the recess 7 in the hinge leaf 6
5 whereupon the screen door with the hinges attached is removed. To hang the screen door all that is necessary is to place the hinge 6 in the recess 10 and pull the bolt 14 downwardly into the recess 7 of the hinge leaf 6 whereupon the door is secured in position.

I may in some instances mount the bolt 14 on the hinge leaf 6 and form a keeper in the plate 9, or I may place two bolts on the hinge leaf 6 with suitable keepers on the face plate 9 and operate said bolts simultaneously by a cam on the hinge leaf 6.

It will be understood that in places where it is desired to place a window screen on a hinge so that the glass windows may be cleaned without entirely removing the screen this improved hinge is adapted for such use.

What I claim is:

1. A hinge hanging plate having a recess in its outer face adapted to receive the leaf of a hinge, a slot through the plate at the upper end of said recess, and a bolt mount-

ed on said plate and adapted to project into said recess, and means holding said bolt in its operative and inoperative position.

2. A hinge hanging plate having a recess in its outer face adapted to receive the leaf of a hinge, a slot through the plate at the upper end of said recess, and a bolt mounted on said plate and adapted to project into said recess and slot, and a spring to frictionally hold the bolt in its adjusted positions.

3. The combination with a hinge hanging plate having a recess in its outer face adapted to receive the leaf of a hinge, a slot through the plate at the upper end of said recess, and a bolt mounted on said plate and adapted to project into said recess and slot, of a hinge comprising two leaves, one of which is imperforate, a projection on the under face of said imperforate leaf, and a recess in the outer face of said imperforate leaf, said last named recess registering, when the parts are in assembled position, with the slot in said plate.

In testimony whereof I affix my signature.

CHARLES F. GESCHICKTER.
